(57) **CLAIM**

The ornamental design for a cover for a surface mount control box, as shown and described.

DESCRIPTION

FIG. 1 is a perspective view of a cover for a surface mount control box of the present invention.

FIG. 2 is a perspective view of the cover for a surface mount control box of FIG. 1, with the cover in the closed position. FIG. 3 is a top view of the cover for a surface mount control box of FIG. 1, with the cover in the closed position.

FIG. 4 is a top view of the cover for a surface mount control box of FIG. 1.

FIG. 5 is a left side view of the cover for a surface mount control box of FIG. 1.

FIG. 6 is a right side view of the cover for a surface mount control box of FIG. 1.

FIG. 7 is a front view of the cover for a surface mount control box of FIG. 1.

FIG. 8 is a back view of the cover for a surface mount control box of FIG. 1 with the cover in the closed position; and,

FIG. 9 is a bottom view of the cover for a surface mount control box of FIG. 1.

The broken lines in FIGS. 1–9 of the surface mount control box to which the claimed cover is mounted is for illustrative purposes only and forms no part of the claimed design.
